CHRISTMAS TREE ORNAMENT OR SIMILAR ARTICLE

Jack Burnbaum, 55 Lakeview Ave., Newton, Mass.

Filed Mar. 22, 1960, Ser. No. 59,834

Term of patent 14 years

(Cl. D29—1)

FIG. 1

FIG. 3

Fig. 1 is a top plan view of a Christmas tree ornament showing my new design,

Fig. 2 is a side elevational view thereof, and

Fig. 3 is a bottom plan view thereof.

I claim:

The ornamental design for a Christmas tree ornament or similar article, substantially as shown.
